ANCHOR

William J. Washam, Harrisonburg, Va.

Application December 12, 1944, Serial No. 567,860

4 Claims. (Cl. 189—92)

1

The invention relates to an anchoring device, and more especially to an expandible anchoring member.

The primary object of the invention is the provision of a device of this character, wherein it can be introduced within a bore within a foundation and automatically locked therein, yet it can be released when the occasion requires, and when locked will firmly and securely hold a guy rod or cable fast in place for supporting purposes.

Another object of the invention is the provision of a device of this character, wherein the holding power thereof is materially increased, it having spreading wings or blades which assure firm and secure anchorage in earth, and these wings or blades can be locked in holding position or adjustment, and readily released for the removal of the device, when it is desired to do so.

A further object of the invention is the provision of a device of this character, wherein the securing blades or wings are linked in a manner that they can be uncoupled with ease and dispatch for the easy removal of the device, the latter being of novel construction, and unique in the arrangement of its parts.

A still further object of the invention is the provision of a device of this character, which is simple in construction, thoroughly reliable and efficient in operation, strong, durable, readily and easily applied and removed, assuring a firm anchorage, with maximum holding power, and inexpensive to manufacture and install.

With these and other objects in view, the invention consists in the features of construction, combination and arrangement of parts as will be hereinafter more fully described, illustrated in the accompanying drawings, which show the preferred embodiment of the invention, and pointed out in the claims hereunto appended.

In the accompanying drawings:

Figure 1 is a side elevation of a device constructed in accordance with the invention showing it being moved to an applied position.

Figure 2 is a fragmentary side view looking toward the outer face of one of its blades or wings.

Figure 3 is a sectional view taken on the line 3—3 of Figure 1 looking in the direction of the arrows.

Figure 4 is a view similar to Figure 1 showing the device in anchored position.

Figure 5 is a view similar to Figure 4 showing the device adjusted for the unanchoring thereof.

Figure 6 is a sectional view taken on the line 6—6 of Figure 3 looking in the direction of the arrows.

2

Figure 7 is a sectional view taken on the line 8—8 of Figure 4 looking in the direction of the arrows.

Figure 8 is a detail plan view of one of the links 5 for the blades or wings.

Figure 9 is a view similar to Figure 8 of the other link.

Figure 10 is a detail plan view showing the blades or wings in separated relation for hinge 10 coupling thereof.

Similar reference characters indicate corresponding parts throughout the several views in the drawings.

Referring to the drawings in detail, A designates generally a bore within the earth, while B denotes in entirety the earth anchor or holding device constructed in accordance with the invention, which comprises a hold-down shank 10, having an outer eye terminal 11 to which is attached a guy wire, cable or the like, not shown. This shank 10 has centrally threaded therein an adjusting stem 12, which functions as a bolt and protrudes through the inner end of such shank for play through a clearance 13 therefor created 25 in a separable pintle hinge 14 swingingly coupling together a pair of anchoring blades or wings 15, which are outwardly tapered and have curved tips 16 for biting engagement in the earth on the spreading of the said wings or blades when countersunk in such earth, as best seen in Figure 4 of the drawings.

The wings or blades 15 have pivoted thereto spreader links 17, which have pivoted thereon separably interfitted coupling nuts 18, one being 35 formed with a bifurcation 19, and the other formed with a threaded hole 20, respectively. The bifurcated nut 18 tops the threaded hole nut, and into the hole 20 of the latter nut is detachably engaged the end 21 of the stem 12, which 40 end 21 has an annular abutment shoulder 22 for contacting the nut having the bifurcation 19, so that both nuts will be separably coupled together by this end 21, as best seen in Figure 3 of the drawings.

45 The shank 10 at its inner end is formed with an externally enlarged head 23 which when contacting the hinge 14 locks the wings or blades 15 in an outwardly spread condition and in anchoring position, as best seen in Figure 4 of the drawings, this being effected by turning the shank 10 on the stem 12 in one direction, then by reverse turning of such shank the blades or wings 15 can be released from locked condition, which is best seen in Figure 1 of the drawings.

55 The stem 12 is provided with a longitudinally

extending mutilated thread area forming an over-running clutch surface 24 in cooperation with a ratchet acting clutch ball 25 freely counter-seated at 26 in the head 23, and held removable by a plug 27 threaded therein. Thus, the shank 10 will turn on the stem 12 in one direction through the threaded connection therewith, but will be held locked against turning in a reverse direction, and in this manner, the stem 12 can be detachably engaged and released from the nuts 18, as best seen in Figure 5 of the drawings. When the nuts 18 are uncoupled, as shown in Figure 5 of the drawings, the device can be withdrawn from the bore A in the earth for the freeing of the anchorage therewith.

The hinge 14 cannot be separated when the stem 12 is engaged in the clearance 13, and to effect the separation of the wings or blades 15, this stem must be detached from the shank 10. On the form shown in Figure 10, my hinge is shown with two spaced interengaging hinge lugs (28) on the butts of the wings (15), one of which lug is off-set inwardly from the side edge of the wing, while the other lug is flush with the side edge of the wing. The off-set lug of each wing carries the hinge pin (29), while the other lug has the pin receiving opening (30). By this arrangement when the wings are hinged together a space provides a clearance for the stem (12).

To anchor the device B, the parts thereof are arranged as is clearly disclosed in Figure 1 of the drawings, and when anchored, the device will set as shown in Figure 4, then for removal of such device, the parts thereof will have been adjusted as shown in Figure 5 of the said drawings.

The device B affords a tight safe anchorage, and is easily applied and removed.

What is claimed is:

1. A device of the kind described, comprising a shank means on the upper end of said shank for engaging a guy wire or the like, a stem threaded

in said shank through one end thereof, spreading wings loosely hinged to each other and slidable on the stem, and linkage pivoted to the wings and detachably coupled to the stem.

2. A device of the kind described, comprising a shank means on the upper end of said shank for engaging a guy wire or the like, a stem threaded in said shank through one end thereof, spreading wings loosely hinged to each other and slid-
10 able on the stem, linkage pivoted to the wings and detachably coupled to the stem and means on the shank for engaging the wings and locking the wings in spread relation to each other.

3. A device of the kind described, comprising a shank, means on the upper end of said shank for engaging a guy wire or the like, a stem threaded in said shank through one end thereof, spreading wings loosely hinged to each other and slid-
20 able on the stem, linkage pivoted to the wings and detachably coupled to the stem, means on the shank for engaging the wings and locking the wings in spread relation to each other and means co-acting with the shank and stem to clutch these together for preventing turning movement with relation to each other in one direction.

4. A device of the kind described, comprising a shank, means on the upper end of said shank for engaging a guy wire or the like, a stem threaded on said shank at one end thereof, wings formed each with spaced hinge lugs on its butts one of which is off-set inwardly from the side edge of the wing and carries a hinge pin, and the other lug having a pin receiving opening so that when the wings are hinged together a clearance to receive the stem is provided therethrough, means coupled with the stem and engaging the wings to spread the same, and means for locking the wings in spread relationship.

WILLIAM J. WASHAM.
